Attorney

UNITED STATES PATENT OFFICE.

JOSEPH A. HROMADKO, OF NEW HAVEN, CONNECTICUT, ASSIGNOR TO THE MOTOR RADIATOR & MANUFACTURING CORPORATION, A CORPORATION OF DELAWARE.

RADIATOR.

1,376,882.

Specification of Letters Patent.

Patented May 3, 1921.

Application filed October 14, 1919. Serial No. 330,597.

To all whom it may concern:

Be it known that I, JOSEPH A. HROMADKO, a citizen of the United States, residing at New Haven, in the county of New Haven 5 and State of Connecticut, have invented certain new and useful Improvements in Radiators, of which the following is a full, clear, and exact specification.

This invention relates to radiators for 10 motor vehicles, and has for its object to simplify the construction of such radiators, reduce the weight thereof, and improve the circulation and radiation of heat therein.

It is the aim of the invention to produce 15 a radiator of thin plates which may be stamped or pressed out from the same pattern and fastened together in oppositely facing pairs to form sections any number of which may be assembled to construct the desired size of radiator. The invention also 20 contemplates the provision of horizontal water circulating passages between the vertical water passages across the air passages, so that the radiating efficiency of the radiator will be increased by the horizontal 25 circulation of the water from side to side of the radiator as well as vertically from bottom to top thereof. Other objects will appear as the description proceeds.

30 The invention will be first hereinafter described in connection with the accompanying drawings, which constitute part of this specification, and then more specifically defined in the claims at the end of the 35 description.

In the accompanying drawings, wherein similar reference characters are used to designate corresponding parts throughout the several views:

40 Figure 1 is a front elevation of a radiator constructed substantially in accordance with this invention.

Fig. 2 is a section on the line II—II of Fig. 1.

45 Fig. 3 is a section on the line III—III of the same figure.

Fig. 4 is a top plan view of three of the radiator sections assembled.

50 Fig. 5 is a horizontal section through the same number of sections as on the line V—V of Fig. 2.

Fig. 6 is a similar view of a modified form of radiator with the transverse water passages, and

Fig. 7 is a section on the line VII—VII of Fig. 2.

In Figs. 1, 2 and 3, the frame of the radiator is indicated at 1 with the upper and lower headers 2 and 3. The body of the radiator is composed of a plurality of sections 4 each comprising two similarly formed and oppositely facing plates 5 and 6 having overlapping flanges 7 at their upper and lower edges and two series of staggered protuberances 8 and 9 pressed therefrom in opposite directions.

The protuberances 8, which extend inwardly of each section, are preferably larger than the protuberances 9 which extend outwardly of each section, and both sets of 70 protuberances are preferably shaped like truncated cones. The protuberances 8 of the plates constituting each section abut against each other in the air passages 10 formed between said plates, thus forming additional 75 water circulating spaces which protrude directly into the air passages.

At the front and rear edges of the plates 5 and 6 of each section there are formed outwardly turned flanges 11 and 12 which are 80 joined together by solder or the like, as at 13, so as to form the vertical water passages 14 between each pair of adjacent sections 4. The protuberances 9 are flush with said flanges 11 and 12 on the respective plates 5 85 and 6, and abut against one another to properly space the sections apart.

As illustrated in Fig. 6, horizontal transverse water passages 15 may be formed between the protuberances 8 by interlocking 90 the punched out ends of said protuberances as at 16, one having an extended neck portion extending into and suitably secured to the other. This construction provides for the circulation of the water from side to 95 side of the radiator as well as from bottom to top.

Having thus described my invention, what I claim as new and desire to secure by Letters Patent of the United States is:—

100 1. A radiator comprising sections each consisting of duplicate opposed plates arranged parallel to each other and connected together at the upper and lower edges to form air passages between them, said plates 105 having protuberances on both faces thereof pressed out from the sheets of which the plates are composed, the inwardly extending

- protuberances having their ends contacting with one another on the opposed plates comprising the same section and forming spacing means for said plates and also additional 5 water circulating spaces, said plates having outwardly turned flanges on their front and rear edges joined to similar flanges on the adjacent sections to form the water circulating 10 passages of the radiator, the outwardly extending protuberances on the plates of each section being of the same extent as said flanges and having their ends abutting against those of the adjacent section for spacing the sections apart.
- 15 2. A radiator comprising sections each consisting of duplicate opposed plates arranged parallel to each other and connected together at their upper and lower edges to form air passages between them, said plates 20 having protuberances on both faces thereof pressed out from the sheets of which the plates are composed, the inwardly extending protuberances being larger than the outwardly extending protuberances and having 25 their ends contacting with one another on the interior of each section to space the opposed plates of each section apart and form additional water circulating spaces, said plates having outwardly turned flanges on 30 their front and rear edges joined to similar flanges on the adjacent sections to form the water circulating passages of the radiator, the outwardly extending protuberances on the plates of each section being flush with 35 said flanges and having their ends abutting against the ends of the corresponding protuberances of the adjacent sections for spacing the sections apart.
3. A radiator comprising sections each 40 consisting of duplicate opposed plates arranged parallel to each other and connected together at their upper and lower edges to

form air passages between them, said plates having protuberances on both faces thereof pressed out from the sheets of which the 45 plates are composed, the inwardly extending protuberances having their ends engaging one another on the opposed plates of each section and having passages through them communicating with the water circulating 50 passages between the adjacent sections, thus providing for the horizontal as well as the vertical circulation of the water in the radiator and additional water circulating spaces in said protuberances which extend 55 inwardly of the individual sections, said plates being connected along their front and rear edges to form the water circulating passages, and the outwardly extending protuberances on the plates of each section having their ends abutting against the corresponding ends of the protuberances of the adjacent sections for spacing said sections apart.

4. A radiator comprising sections each 65 consisting of spaced plates arranged parallel to each other and connected together at their upper and lower edges to form air passages between them, said plates having outwardly turned flanges at their front and rear edges 70 joined to similar flanges on the adjacent sections to form the water circulating passages of the radiator, and outwardly extending protuberances pressed from said plates of each section and having their outer 75 ends flush with the flanges on the same plates, said protuberances having their ends abutting against the ends of those on the adjacent sections for spacing the sections apart.

In testimony whereof I have signed my name to this specification.

JOSEPH A. HROMADKO.
